CLAIM

The ornamental design for a volatile dispenser, as shown and described.

DESCRIPTION

FIG. 1 is a left, top, frontal perspective view of a volatile dispenser embodying our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a left, top, frontal perspective view of a second embodiment of our new design;

FIG. 9 is a front elevational view thereof;

FIG. 10 is a left side elevational view thereof;

FIG. 11 is a right side elevational view thereof;

FIG. 12 is a rear elevational view thereof;

FIG. 13 is a top plan view thereof;

FIG. 14 is a bottom plan view thereof;

FIG. 15 is a left, top, frontal perspective view of a third embodiment of our new design;

FIG. 16 is a front elevational view thereof;

FIG. 17 is a left side elevational view thereof;

FIG. 18 is a right side elevational view thereof;

FIG. 19 is a rear elevational view thereof;

FIG. 20 is a top plan view thereof; and,

FIG. 21 is a bottom plan view thereof.

The broken line representations of front vents in FIGS. 8-11, 13-18, and 20-21, side and bottom vents in FIGS. 8, 10-12, 15, 17-19, and 21, a raised section in FIGS. 8-11, 13, 15-18, and 20, an on/off switch in FIGS. 8, 9, 11-16, and 18-21, mating lines in FIGS. 8, 10-15, and 17-21, and a clip in FIGS. 15, and 17-21 are for purposes of illustration only and form no part of the claimed design.
